UNITED STATES PATENT OFFICE.

CHARLES W. UMHOLTZ, OF BRISTOL, VIRGINIA.

EXHAUST-NOZZLE.

SPECIFICATION forming part of Letters Patent No. 487,137, dated November 29, 1892.

Application filed August 12, 1892. Serial No. 442,871. (No model.)

To all whom it may concern:

Be it known that I, CHARLES W. UMHOLTZ, of Bristol, in the county of Washington and State of Virginia, have invented a new and 5 Improved Exhaust-Nozzle for Locomotives, of which the following is a full, clear, and exact description.

My invention relates to exhaust-nozzles such as are shown and described in the application for Letters Patent of the United States, Serial No. 427,986, filed by me April 6, 1892, and allowed July 20, 1892.

The object of the present invention is to provide a new and improved exhaust-nozzle, 15 which is simple and durable in construction and very effective in operation.

The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

25 Figure 1 is a transverse section of the improvement as applied. Fig. 2 is a sectional side elevation of the improvement. Fig. 3 is a plan view of the same, and Fig. 4 is a sectional front view of part of the improvement.

30 The stand-pipe A of the locomotive is connected in the usual manner with the exhaust-passages leading from the locomotive-cylinders, and the said stand-pipe may be single or have a division-wall, as illustrated in Fig. 1.

35 The upper end A' of the stand-pipe A is contracted and circular in form, as is plainly shown in the drawings, and in this end are held set-screws B, engaging lugs C, projecting from the lower end of the nozzles D held 40 concentric at its lower end in the reduced end A' of the stand-pipe A, so as to form a space between the inner surface of the end A' and the lower end of the nozzle D. Above the nozzle D is arranged an inverted cone E, the

axis of which is in line with the axis of the 45 nozzle D, as shown in the drawings. The cone E is secured at its base on an arm F, mounted to slide vertically in guideways G, formed on one side of the stand-pipe A. The arm F is adapted to be secured in place by a 50 bolt H, passing through a vertical slot I, formed in the arm F, the said bolt screwing in the stand-pipe A with its head abutting on the outer surface of the arm F.

It is understood that the cone E serves to 55 spread the exhaust-steam passing up through the nozzle D, so as to pass unobstructed through the stack of the locomotive-boiler. It is further understood that by raising and lowering the said cone E the spreading is de- 60 creased or increased as the cone moves farther away from or nearer to the said nozzle D.

Having thus fully described my invention, I claim as new and desire to secure by Letters Patent—

65 1. The combination, with the stand-pipe, of the nozzle D, entering at its lower end the upper end of the stand-pipe and spaced therefrom, and transverse centering-screws B, passing through the upper end of the stand-pipe 70 and engaging the tube and holding it concentric with the stand-pipe, substantially as described.

2. The combination, with the stand-pipe and its concentric spaced nozzle, of the vertical guideway on the outer side of the stand-pipe, an angular arm, the vertical member of which is mounted in or on said guideway having a longitudinal slot, a set-screw extending through the slot into the stand-pipe, 80 and a depending inverted cone on the transverse member of the arm with its axis in line with that of the nozzle, substantially as described.

CHARLES W. UMHOLTZ.
